UNITED STATES PATENT OFFICE.

PAULINA A. STOCKTON, OF LAKE, TENNESSEE, ASSIGNOR OF ONE-THIRD TO ISAAC R. STORIE AND ONE-THIRD TO GEORGE STOCKTON, BOTH OF RUGBY, TENNESSEE.

CABINET.

1,177,734.

Specification of Letters Patent.

Patented Apr. 4, 1916.

Application filed July 19, 1915. Serial No. 40,744.

To all whom it may concern:

Be it known that I, PAULINA A. STOCKTON, a citizen of the United States, residing at Lake, in the county of Fentress and State 5 of Tennessee, have invented certain new and useful Improvements in Cabinets, of which the following is a specification, reference being had to the accompanying drawings.

10 This invention relates to certain improvements in cabinets and has relation more particularly to a device of this general character especially designed and adapted for use in connection with sewing machines or 15 the like; and it is an object of my invention to provide a cabinet of this character having novel and improved means whereby the work is prevented from becoming soiled or otherwise damaged by contact with the 20 surface on which the cabinet is rested.

Furthermore, it is an object of my invention to provide, in combination with a cabinet of this general character, a pivoted leaf having coacting therewith novel and 25 improved means whereby the same may be supported at varying positions relative to the surface of the cabinet.

The invention consists in the details of construction and in the combination and arrangement of the several parts of my improved cabinet whereby certain important advantages are attained and the device is rendered simpler, less expensive and otherwise more convenient and advantageous for 35 use, all as will be hereinafter more fully set forth.

The novel features of the invention will be carefully defined in the appended claims.

In order that my invention may be the better understood, I will now proceed to describe the same with reference to the accompanying drawings, wherein—

Figure 1 is a view, partly in elevation and partly in section, illustrating a cabinet 45 having an embodiment of my invention applied thereto; and Fig. 2 is an enlarged fragmentary view, partly in section and partly in elevation, illustrating the means herein disclosed, for locking the swinging leaf or shelf in its various adjustments.

As disclosed in the accompanying drawings, C denotes a cabinet of any ordinary or preferred construction having mounted upon the table 2 thereof the sewing mecha-

nism 3 adapted to be driven by the wheel 4 in a well known manner.

5—5 denote the end members of my improved cabinet, the lower extremities whereof at the rear being connected by the panel 6 and the space between the upper longitudinal edge of the panel 6 and the rear edge of the table 2 is adapted to be closed by the leaf 7 pivotally secured, as at 8, to the rear marginal portion of the table 2 and capable of vertical swinging movement with the 60 forward or free longitudinal margin thereof disposed upwardly on a predetermined incline, as at 9, to form, when in an elevated adjustment, a receptacle to receive the work after being operated upon by the sewing 65 mechanism to prevent such work from becoming soiled or otherwise damaged as would possibly occur should such work be permitted to drop or fall to the surface on which the cabinet is rested. Pivotally secured to each of the end members 5 adjacent the upper longitudinal edge of the panel 6 and to an end marginal portion of the leaf or shelf 7 is a toggle member 10 adapted to serve as a support for maintaining the shelf or leaf 7 in an elevated adjustment, and it is to be observed that this toggle member 10 when folded extends inwardly between the end members 5 and below the wheel 4 so that no obstruction will 75 be offered to the rotation of the wheel 4 when the shelf or leaf 7 has been adjusted into a lowered position or in a position to close the space between the panel 6 and the 80 table 2.

As herein embodied, each of the toggle members 10 comprises two sections, the adjacent ends of which being pivotally connected one with the other, as indicated at 11, and such sections are of such a length as to cause the shelf or leaf 7 when at the limit of its upward movement to assume a position slightly below the plane of the upper surface of the table 2 and preferably a distance sufficient to have the upper edge of the 85 curved or inclined portion 9 substantially flush with the upper surface of the table 2.

The pintle 12 comprised in the hinged connection 11 is capable of endwise movement so that the same may be extended within 105 the arcuately arranged series of openings 12 produced in the adjacent end panel 5 so that the shelf or leaf 7 may be locked in

closed adjustment relative to the cabinet or may be maintained at various angles of inclination, the intermediate adjustments of the shelf or leaf 7 being preferably for the purpose of ventilation when it is not especially desired to use the shelf to receive the work after it has been operated upon by the sewing mechanism.

From the foregoing description, it is thought to be obvious that a cabinet constructed in accordance with my invention is of an extremely simple and comparatively inexpensive nature and is particularly well adapted for use by reason of the convenience and facility with which it may be assembled, and it will also be obvious that my invention is susceptible of some change and modification without material departure from the principles and spirit thereof and for this reason I do not wish to be understood as limiting myself to the precise arrangement and formation of the several parts herein shown in carrying out my invention in practice.

25 I claim:

1. In combination with a cabinet, a shelf pivotally engaged therewith, a supporting member for the shelf operatively engaged

therewith and with the cabinet, said member comprising sections having their adjacent extremities pivotally connected, the pintle comprised in said pivotal connection being capable of endwise movement, the portion of the cabinet adjacent the member being provided with means coacting with the pintle for locking the shelf against upward movement when in lowered position.

2. In combination with a cabinet, a shelf pivotally engaged therewith, a supporting member for the shelf operatively engaged therewith and with the cabinet, said member comprising sections having their adjacent extremities pivotally connected, the pintle comprised in said pivotal connection being capable of endwise movement, a portion of the cabinet being provided with perforations to receive the pintle whereby the shelf is maintained against upward swinging movement when in lowered position.

In testimony whereof I hereunto affix my signature in the presence of two witnesses.

PAULINA A. STOCKTON.

Witnesses:

G. W. WOOD,
PEARSON PILE.
